RAILWAY-TRAIN-CONTROL MECHANISM.

1,334,520.

Specification of Letters Patent. Patented Mar. 23, 1920.

Application filed October 28, 1918. Serial No. 259,942.

To all whom it may concern:

Be it known that we, FOREE CHITTENDEN and HOWARD S. FOLKER, citizens of the United States, said CHITTENDEN a resident of Oakland, in the county of Alameda and State of California, and said FOLKER a resident of the city and county of San Francisco, State of California, have invented certain new and useful Improvements in

10 Railway - Train - Control Mechanism, of which the following is a specification.

The present invention relates to a means for establishing a communication between a roadway and a railway vehicle, whereby 15 complicated electrical mechanism and intricate wiring systems are dispensed with and a simple magnetic apparatus, the operation of which is controlled by suitable permanent track magnets, is provided.

20 The principal objects of the invention are to provide an apparatus capable of being operated solely by magnetism at any desired point on a railway at which is positioned a controlling member, but more particularly 25 at a block entrance, the operation of said apparatus being dependent on the position of the keeper for the permanent controlling magnet, and to provide, further, an apparatus which is capable of operation 30 on the movement of the vehicle in either direction, and whereby the vehicle air line may be so operated or controlled that a signal may be transmitted to the vehicle operator, or the further movement of the vehicle may be automatically controlled either 35 by operating the brakes controlling the throttle or in any other desired manner.

The invention consists broadly in a permanent track magnet provided with a movable 40 keeper automatically or manually operated and relatively to which is movable, by the movement of the vehicle, a suitable member or signal receiving mechanism normally held in inoperative position by the magnetic flux of a suitable comparatively weak magnet associated therewith, the signal receiving mechanism being moved to operative position by the neutralizing of the magnetism 45 thereof on the movement of the same over the permanent magnet when the keeper thereof is in open position.

With the above mentioned and other objects in view, the invention consists in the novel construction and combination of parts

hereinafter described, illustrated in the accompanying drawings and pointed out in the claims hereto appended; it being understood that various changes in the form, proportion, size, and minor details of construction within the scope of the claims may be resorted to without departing from the spirit or sacrificing any of the advantages of the invention.

To more fully comprehend the invention, reference is directed to the accompanying drawings, wherein—

Figure 1 is a diagrammatic view of a section of a railway illustrating the permanent track magnets at the entrance and exit of the block of a single track railroad and a train control unit carried by the railway vehicle.

Fig. 2 is a view in side elevation of a section of a railway and a portion of the vehicle, with the preferred embodiment of our invention illustrated in connection therewith.

Fig. 3 is a longitudinal sectional view of the vehicle unit illustrating the signal receivers and the corrector.

Fig. 4 is a vertical sectional view of one of the receivers taken on line 4—4 of Fig. 3.

Fig. 5 is a vertical sectional view taken on line 5—5 of Fig. 4.

Referring more particularly to the drawings, wherein like characters of reference designate corresponding parts, a railway is indicated in Figs. 1 and 2 in which the rails 1 are preferably divided in any suitable manner, as by insulations 2 into blocks A 90 and B. At the entrance of each block is positioned preferably between the rails 1, a permanent magnet 4 having a movable keeper 5 automatically or manually operated by any type of mechanism, either controlled from a tower or by the movement of the vehicle from block to block, one form of mechanism being illustrated in pending application Serial Number 223,281, filed March 19, 1918.

In the illustration in Fig. 1 a single track railway is illustrated to accommodate the movement of trains in both directions, and in such an installation a permanent magnet is provided at each end of each block, the adjacent magnets of abutting blocks facing each other with their poles reversed.

The permanent magnet 4 as illustrated in

the drawing, is considerably larger than the magnetic means carried by the vehicle hereinafter described, and owing to its increased size the same is of greater power than said 5 hereinafter described magnetic means in order to insure the correct operation of the various elements.

Operating on the rails 2 is a vehicle truck 6 supporting a suitable vehicle 7, the truck 10 carrying an operating unit 8 disposed to pass over the permanent magnets within the magnetic field thereof during the movement of the vehicle thereover.

The unit comprises an elongated plate or 15 bed member 9 disposed parallel with the rails and depending from the said plate at its opposite ends are the hollow signal receivers 10, each having interposed a head 11 between its upper open end and the underside of member 9 (Figs. 3 and 4 of the drawings). The heads are each provided with a centrally disposed opening 12, within which is mounted the tubular bushing 13 having a seat 14 therein, on which rests a flexible 20 valve seat or disk 15 held in position on the seat by a suitable retaining ring 16, the valve seat being formed with the opening 16' in its center smaller than the opening afforded by the seat 14. An air release port 17 is 25 provided in the bushing 13 below the seat 14, and from the same extend the laterals 18 leading through the head to the atmosphere (Fig. 4 of the drawings).

At a point below the port 17 is mounted 30 in the underside of the tubular bushing a tubular valve guide 19, in which reciprocates the upper end of a valve 20 carrying at its lower end the armature 21, coöperating with the poles of an electromagnet 22. The yoke 40 35 of the magnet is formed with a tubular bore 24 in which is held the guide 19, and through which passes the valve 20. The magnet is normally maintained energized by a battery 25 (Fig. 2 of the drawings) in circuit therewith through leads 26', and preferably carried by the vehicle. The tubular bushing 13 communicates with the lateral air supply 26 formed in the bed 9 and leading from the main supply duct 30, connected 45 with the train air line 31, Fig. 1 of the drawings, and which is controlled by a valve 31'.

The valve 20 is guided in its movement by a stationary pin 32 (Fig. 4 of the drawings) 50 passing through an opening 33 in the armature 21, the valve when unseated resting on a spring pressed plunger 34 mounted in a guide 35 carried by a closure plate 36 secured to the lower end of each signal receiver.

Each plunger is normally forced upwardly 55 by a coiled spring 37 (Figs. 3 and 4 of the drawings) within the guide 35, and which is adapted to restore the valve to closed position after the air supply under pressure has 60 been momentarily shut off to the air line 31.

The energizing of the magnet 22 is sufficient to maintain the valve 20 in closed position against the underside of the flexible member 15. However, on the momentary reversing of the magnetism of the magnet 70 22 by the magnetic field of one of the permanent magnets 4, the slightest downward movement of the valve 20 will expose the valve area of the upper end thereof to the air pressure in the lateral 26, and which air 75 pressure is sufficient to maintain the valve downwardly pressed against the action of the spring 37, and power of magnet 22, permitting the air from line 31' to escape through the outlets 18, until such time as the 80 air pressure is interrupted in lateral 26, when the spring 37 will move the valve to closed position seating the upper end thereof against the underside of the disk 15 formed with the opening 16' of an area less than 85 the area of the valve end, thus reducing the area of the valve end exposed to the air pressure, enabling the magnet 22 to maintain the armature 21 in engagement therewith, holding the valve end against the underside of the flexible member 15. The member 15 being flexible, is forced by the air pressure against the end of valve 20, maintaining a tight seal thereover at all 90 times during the seating of the valve member. 95

From the magnet extend the pole pieces 38 projecting outwardly from the receivers 10 to overlie the poles of the permanent track magnets 4 and carrying on their ends 100 shoes 39 (Fig. 4 of the drawings), the poles of the magnets of the respective receivers being reversed from each other, as in Fig. 1, so that the poles of the last receiver in the direction of travel of the vehicle will lie 105 reversed to the poles of the permanent track magnet of the block into which the vehicle is moving. A safety channel 36' (Fig. 3 of the drawings) extends from the outer end of each lateral 26 through the receiver 10, 110 said channels each being closed at its lower end by the plates 36, thus insuring an opening of the air line on the accidental removal or fracturing of the plate or receiver casing. 115

Secured to the underside of the bed member 9, between the signal receivers 10, is a signal corrector 40 (Figs. 3 and 5 of the drawings) in the form of a shell 41, open at its upper end and closed at its lower end. Within the upper open end of the shell is 120 received the member 41' formed with the main bore 42 therein, communicating at one end with the main supply duct 30 and laterally from the lower end of said bore extend the bores 43 (Fig. 3 of the drawings), one 125 communicating at its discharge end with the inlet end of one of the lateral supply ducts 26. A valve 44 is positioned in the shell 41 in line with the bore 42 and is adapted, on the upward movement thereof to be received in 130

said bore and close the same. The valve operates at its lower end in a guide 44' (Figs. 3 and 5 of the drawings) and carries an armature or plate 45 normally lying below the spaced inner ends of magnetic conductor arms 46, the outer ends of which extend laterally from opposite sides of the lower end of shell 41 and carry conductor shoes 47. The corrector valve 41 is adapted 5 to be operated by magnetism of any polarity to close the bore 43 and interrupt the flow of air therethrough. Hence it will be unnecessary to operate valve 31' in order to interrupt the flow of air in bore 43, enabling any 10 installation of the double receiver type with the corrector interposed between the same to operate on a single or double track system, as, for example, in the system illustrated in Fig. 1.

Should, for any reason, the keeper of the magnet of the block the vehicle is leaving be disengaged from its magnet, as for example due to the operation of the keeper controlling means one form of which is illustrated 20 in copending application Serial No. 223,281, and which block magnet is for controlling the entrance of vehicles traveling in an opposite direction on entering the block, the first receiver in the direction of travel of 25 the vehicle will be operated. Immediately thereafter the corrector valve will be operated, shutting off the air supply and permitting of the automatic restoring of the valve of the operated receiver to normal position, 30 thereby enabling the correct signal to be communicated to the last receiver on the same passing into the block the vehicle is 35 entering or is about to enter.

The parts being assembled as in the drawings, the operation of the apparatus is as follows:—The vehicle moving in the direction of the arrow 50, Fig. 1, from block A to block B, the signal receiver C of the unit will first pass over the permanent track 40 magnet 4 at one end of the block A, the poles of which are reversed to the poles of the magnet of receiver C. Should for any reason the keeper 5 of said magnet be disconnected from the poles thereof, creating a 45 magnetic field in proximity to said poles, the valve of the receiver C will be operated, opening the air line 31 to the atmosphere. However, inasmuch as this receiver is designed for controlling the opening of the 50 air-line to the atmosphere on the movement 55 of the vehicle in a direction reverse to the arrow 50, this opening of the valve 20 of the receiver C is immediately corrected by the operation of the valve 44 of the signal corrector immediately following the receiver C over the permanent magnet 4, the operation 60 of the corrector valve momentarily and automatically interrupting the air pressure from line 31, permitting the valve 20 of signal receiver C to assume its closed position. If

block B is clear or unoccupied the keeper of magnet 4 at the entrance thereof will connect the poles of said magnet, and the receivers C and D to the corrector will pass 70 thereover without operation.

Assuming the block B to be occupied, the keeper of the magnet 4 at the entrance thereof is adapted to be moved by its operating means set forth in the before mentioned copending application Serial No. 75 223,281 to lie in dotted line position—Fig. 2, permitting the creating of a magnetic field at the ends of the poles thereof.

On the passing of the receiver C within the magnetic field of said magnet numeral 80 4 of block B, the valve thereof will not be operated, as the poles of said receiver and magnet coincide, as do the poles of the receiver D and the magnet at the end of the block A the vehicle is leaving. The corrector 85 will be operated on passing over said magnet as the same has no polarity. However, the operation of the corrector is immaterial, as the receiver in advance thereof has not been operated. The receiver D passing 90 within the magnetic field of the magnet 4 at the entrance of the block B will be caused to operate as the poles thereof are reversed to the poles of said magnet, the force of which neutralizes the magnetism of the magnet 22 95 holding the valve thereof closed, permitting the air pressure in line 31 to act against the end of the valve 20 and unseat the same during the momentary passage of the receiver D over said magnet 4 of block B, when the 100 vehicle is traveling in the direction of the arrow 50. The air thus released escaping through laterals 18, during which time the air-line 31 is open to the atmosphere, and which operation continues until such time as 105 the vehicle operator momentarily closes the valve 31', at which time the spring 37 forces the valve upwardly, cutting off the escape of the air through lateral 18 and positioning the armature 21 of said valve within the 110 field of magnet 22, which is of sufficient power to retain said armature in contact therewith to maintain the valve closed.

In the present application it will be apparent that the permanent track magnet at 115 the entrance of the block toward which the vehicle is traveling is the one which controls the release of pressure in the air-line to the atmosphere, and this magnet when its associated keeper is removed from the poles 120 thereof operates the last receiver of the unit passing over the same. Regardless of the direction of travel of the vehicle the corrector is operated by the magnetism of any permanent magnet 4, the keeper of which is 125 disconnected from the poles thereof. However, as this corrector passes within the magnetic field of any given track magnet immediately after the first receiver of the unit 130 passes over the magnet, the corrector imme-

diately closes the air line which might have been opened by the action of the magnetism of the track magnet mentioned. It is apparent, that after the last receiver of the unit is operated there is no means operated by the continued movement of the vehicle to close the air-line, and this air-line is only closed by the vehicle operator closing the valve 31' which permits momentarily releasing the air pressure on the end of the actuated valve 20 permitting the same to be closed and held in closed position by the strength of the magnets 22.

It will be apparent, that by employing the permanent track magnets, each having a removable keeper that all battery mechanisms in connection with the magnets are dispensed with, and as a safety factor, as explained in copending application Serial No. 223,284, should anything happen to the signal system or the block interlock, the keeper of the magnet of the deranged block would automatically drop due to its own weight and the valve of the unit corresponding, to be operated, will be operated by the magnetism of the magnet on the vehicle passing thereover.

In a double track system where the vehicles are moved in a single direction on a given stretch of track but one magnet is needed for each block and that is positioned at the block entrance. However, in the single track system illustrated, where the vehicle travels in both directions on the tracks a magnet is positioned at the opposite ends of each block. If the vehicle is always operated in a forward or single direction one receiver is all that will be necessary. However, a conflict with proper operation is produced by a backing or rearward movement of the vehicles. The polarity of the track magnet is fixed and is the same for all signal locations, one polarity being maintained to the right and the opposite polarity to the left of the vehicle facing the direction of movement. In a backing or rearward movement of the vehicle this arrangement will cause a failure to deliver a signal at the proper location because of like polarity of the poles of the track magnet and the receiver magnet. To remedy this condition, two receiver units are employed, one for operation in each direction with a corrector operated by any polarity interposed between the same.

Having thus described our invention, what we claim as new and desire to protect by Letters Patent is:—

1. A railway signal system including a permanent polarized track magnet, means coöperating with the poles thereof for controlling the magnetic field at the ends of said poles, a signal receiver carried by a railway vehicle and movable through the magnetic field of said permanent track mag-

net, polarized magnetic means for normally maintaining said signal means in inoperative position, the poles of said magnetic means being reversed to the poles of said track magnet whereby the power of said magnetic means is neutralized on the movement of the poles thereof through the magnetic field of said track magnet to permit the operation of said signal.

2. In combination with a railway vehicle having an air line opening to the atmosphere, a valve for normally closing said air line opening to the atmosphere, polarized magnetic means for normally maintaining said valve closed, a permanent polarized track-magnet through the magnetic field of which said valve is movable, means coöperating with the poles thereof for controlling the magnetic field adjacent the ends of the poles of said permanent magnet, the poles of said track magnet being reversed to the poles of said valve magnetic means, whereby the power of said valve magnetic means is neutralized on the movement of the same through the magnetic field of said track-magnet.

3. In combination with a railway vehicle having an air line opening to the atmosphere, a valve for normally closing said air line opening to the atmosphere, polarized magnetic means for normally maintaining said valve closed, a polarized track magnet of greater power than said magnetic means and through the magnetic field of which said magnetic means is movable, means coöperating with the poles thereof for controlling the magnetic field adjacent the ends of the poles thereof, the poles of said track-magnet being reversed to the poles of said valve magnetic means whereby the power of said valve magnetic means is neutralized on the movement of the same through the magnetic field of said track magnet.

4. A railway signal system including a permanent polarized track magnet and associated means coöperating with the poles thereof for controlling the magnetic field adjacent to the ends of said poles, a signal receiver carried by a railway vehicle and movable within the magnetic field of said permanent track magnet, polarized magnetic means for normally maintaining said signal receiver means in inoperative position, said means being less powerful than said track magnet, and with its poles reversed to the poles of said track magnet, said track magnet adapted on the creation of a magnetic field around the poles thereof and on the movement of said signal receiver within said magnetic field to neutralize the magnetism of said magnetic means and permit operation of said signal.

5. A railway signal system including a permanent polarized track magnet and associated means coöperating with the poles

- thereof for controlling the magnetic field adjacent to the ends of said poles, a signal receiver carried by a railway vehicle and movable within the magnetic field of said permanent track magnet, polarized magnetic means arranged with the poles thereof reversed to the poles of said track magnet and for normally maintaining said signal means in inoperative position, said track magnet adapted on the creation of a magnetic field around the poles thereof and on the movement of said signal receiver within the magnetic field thereof to neutralize the magnetism of said magnetic means to permit operation of said signal, and means for restoring said signal receiver to normal inoperative position on the movement of the same without the magnetic field of said track magnet.
6. A railway signal system including a permanent polarized track magnet, a signal receiver carried by a railway vehicle and movable within the magnetic field of said permanent track magnet, polarized magnetic means for normally maintaining said signal means in inoperative position and arranged with its poles reversed to the poles of said track magnet, said track magnet adapted on the movement of said signal receiver within the magnetic field thereof to neutralize the magnetism of said magnetic means and permit operation of said signal, manually controlled means capable of operation to permit the restoring of said receiver to normal inoperative position on the movement of the receiver without the magnetic field of said permanent track magnet, and means associated with the poles of said track magnet for controlling the magnetic field adjacent the ends of said poles.
7. A railway signal system including a signal receiver, polarized magnetic means for retaining the same in inoperative position, a permanent polarized track magnet of greater strength than said magnetic means and arranged with its poles reversed and the poles of said magnetic means and within the field of which said receiver is movable, said permanent magnet capable of neutralizing the magnetism of said signal receiver to permit the automatic operation thereof and means disposed at the ends of the poles of the permanent track magnet for controlling the magnetic field adjacent the ends of the poles of said permanent track magnet.
8. A railway signal system including a polarized magnetically controlled signal receiver, a permanent magnet within the field of which said receiver is movable and with its poles reversed to the poles of said receiver magnet for neutralizing the magnetism of said signal receiver, means associated with the poles of the track magnet for controlling the magnetic field adjacent the ends of said poles, and means associated with said signal receiver for operating the same on the neutralizing of the magnetism thereof.
9. A railway signal system including a polarized magnetic controlled signal receiver, a permanent magnet within the field of which said receiver is movable and with its poles reversed to the poles of said receiver magnet and capable of neutralizing the magnetism within said signal receiver for operating the same on the neutralizing of the magnetism thereof and means for restoring the signal receiver to normal position on the interruption of said last mentioned means and the movement of said receiver without the magnetic field of said permanent magnet.
10. A railway signal system including a signal receiver, a movable signal control member therein, polarized magnetic means for maintaining the same normally in inoperative position, a permanent polarized track magnet within the field of which said receiver is movable, said magnetic field being capable of neutralizing the magnetism of said magnetic means associated with said movable member to permit the operation of said movable member, and means associated with the poles of said permanent magnet for controlling the magnetic field adjacent the ends of the poles of said permanent track magnet.
11. A railway signal system including a signal receiver, a movable signal control member therein, an air line having an escape and within which said movable member is mounted to normally maintain the same closed, magnetic means for retaining said movable member in a position to close said line, a permanent track magnet and its associated keeper within the field of which said receiver is movable, said keeper controlling the field of said magnet, said magnet being capable on the disengagement of the keeper therefrom of neutralizing the magnetism of said magnetic means associated with said movable member to permit the operation thereof by said air under pressure, manually controlled means within said air line for interrupting the pressure therein to permit the automatic closing of said movable member on the movement of the receiver without the magnetic field of said permanent track magnet.
12. A railway signal system including a signal receiver carried by a railway vehicle, movable signal control means associated therewith, magnetic means for normally maintaining said member in inoperative position, a permanent track magnet within the magnetic field of which said receiver is movable and adapted to neutralize the magnetism of said magnetic means, means under pressure for operating the said signal con-

trol means on the neutralizing of said magnetism, means for restoring said signal control member to inoperative position on the interruption of said pressure operating means and the movement of said receiver without the magnetic field of said track magnet, and means associated with the poles of said track magnet for controlling the magnetic field adjacent the ends of the poles of said track magnet.

13. A railway signal system including a polarized permanent track magnet, a signal receiver member carried by a railway vehicle and including a pair of receiver units, a movable signal control member within each of said units, magnetic means associated with each of said signal receivers for normally maintaining the movable signal control member therein in inoperative position, the poles of said magnetic means being reversed relatively to each other, and the poles of one being reversed relatively to the poles of said permanent track magnet, whereby on the movement of said vehicle within the magnetic field of said permanent track magnet the magnetism controlling the movable signal control member, the poles of which are reversed to the poles of said permanent track magnet may be neutralized, permitting the automatic operation of said control member, and means for controlling the field of said track magnet.

14. In combination with a railway vehicle air-line, a permanent polarized track magnet, polarized magnetic means associated with the vehicle and operated by the magnetism of said track magnet on the movement of said means through the magnetic field of said track magnet for opening said air line to permit the escape of air therefrom, and means associated with the ends of the poles of said track magnet for controlling the magnetic field of said track magnet.

15. In combination with a railway vehicle air line, a polarized permanent track magnet having polarized magnetic means operated by the magnetism of said track magnet for opening said air line to permit the escape of the air therefrom on the movement of the vehicle within the magnetic field of said track magnet, manually operated means within said line and capable of operation to permit the restoring of said operative means to normal position on the movement of said magnetic means without the field of said permanent track magnet, and means associated with the ends of the poles of said permanent magnet for controlling the field of said track magnet.

16. A railway signal system including a polarized permanent track magnet, a railway vehicle provided with the usual air line, means for controlling the escape of the air under pressure therefrom, including a movable valve within said line having a por-

tion thereof exposed to the air pressure therein, magnetic means, the poles of which are reversed to the poles of said permanent track magnet for maintaining said valve in position to close said line, the air under pressure adapted for operating said valve to open said line on the movement of said magnetic means within the magnetic field of said permanent track magnet and the neutralizing of the magnetism thereof, and means for controlling the magnetic field of said track magnet.

17. A railway signal system including a polarized permanent track magnet, a signal receiver member carried by a railway vehicle and including a pair of receiver units successively movable into the magnetic field of said track magnet on the movement of said vehicle thereover, an air line carried by the vehicle and provided with a plurality of outlets, one extending to each receiver, a movable signal control member within each of said units and each normally held against the pressure in said line for closing one of said outlets, magnetic means associated with each of said signal receivers for maintaining said members in their latter position, the poles of said magnetic means being reversed to each other, and the poles of the last one movable into the magnetic field of said track magnet being reversed to the poles of said track magnet, whereby on the movement of said latter receiver within the magnetic field of said track magnet the magnetism will be neutralized permitting said line pressure to move said signal control member to open the outlet controlled thereby, and means for controlling the magnetic field of said track magnet.

18. A railway signal system including a polarized permanent track magnet, a signal receiver member carried by a railway vehicle and including a pair of receiver units successively movable into the magnetic field of said track magnet on the movement of said vehicle thereover, an air line carried by the vehicle and provided with a plurality of outlets, one extending to each receiver, a movable signal control member within each of said units and each normally held against the pressure in said line for closing one of said outlets, magnetic means associated with each of said signal receivers for maintaining said members in their latter position, the poles of said magnetic means being reversed to each other, and the poles of the last one movable into the magnetic field of said track magnet being reversed to the poles of said track magnet, whereby on the movement of said latter receiver within the magnetic field of said track magnet the magnetism of said permanent magnetic means will be neutralized permitting said line pressure to move said signal control member to open the outlet controlled thereby.

means within said line capable of manual operation to interrupt the air supply to said receiver, means for restoring said operated signal control member to normal position on the movement of said signal control member to a point without the magnetic field of said track magnet and the interruption of the air pressure in said line, and means for controlling the field of said permanent magnet.

19. A railway signal system including a permanent polarized track magnet, a signal receiver member carried by a railway vehicle and including a pair of receiver units successively movable into the magnetic field of said track magnet on the movement of said vehicle thereover, an air line carried by the vehicle and provided with a plurality of outlets, one extending to each receiver, a movable signal control member within each of said units and each normally held against the pressure in said line for closing one of said outlets, a movable member positioned between said receiver units and adapted on the movement of the same within the field of said permanent magnet to be operated by the magnetism of said permanent magnet to intermittently interrupt the air pressure in said line in advance of said signal control members, magnetic means associated with each of said signal receivers for maintaining said members in their latter position, the poles of said magnetic means being reversed to each other, and the poles of the last one movable into the magnetic field of said track magnet being reversed to the poles of said track magnet, whereby on the movement of said latter receiver within the magnetic field of said track magnet the magnetism of said track magnet will be neutralized permitting said line pressure to move said signal control member to open the outlet controlled thereby and means for controlling the field of said permanent magnet.

20. A railway signal system including a pair of polarized permanent track magnets arranged in spaced relation to each other with their poles reversed, a railway vehicle, a plurality of polarized signal receivers carried thereby, a signal means controlled thereby, one of said receivers adapted for operation by magnetism of one of said magnets on the movement of the vehicle within the magnetic field thereof, means carried by the vehicle and operated by the magnetism of either of said magnets during the movement of the same through the magnetic field thereof for permitting one of said receivers to remain in operative position after being operated by the magnetism of its co-operating track magnet dependent upon the direction of movement of the vehicle on said railway and means associated with the respective track magnets for controlling the field thereof.

21. A railway signal system including a pair of polarized permanent track magnets arranged in spaced relation to each other with their poles reversed, a railway vehicle, a plurality of polarized signal receivers carried thereby, a signal means controlled thereby, one of said receivers adapted for operation by the movement of one of said track magnets on the movement of the receiver through the field thereof, means carried by the vehicle and operated by both of said magnets on the movement of the same through the magnetic field thereof for permitting the automatic restoring of one of said receivers to normal position after being operated by the magnetism of its co-operating track magnet dependent on the direction of movement of the vehicle on said railway, and means associated with each track magnet for controlling the field thereof.

22. A railway vehicle signal system including a controlling unit, an air line having an escape to the atmosphere, a controlling valve within said unit and closing against the pressure in said air line to interrupt the escape of the same to the atmosphere, an armature associated with said valve, and a magnet associated with the unit and arranged with the terminus of the pole pieces thereof extending laterally from opposite sides of said unit, said magnet attracting said armature to maintain said valve normally seated.

23. A railway vehicle signal system including a controlling unit, an air line passing therethrough and having an escape to the atmosphere, a valve seat within said air line and provided with a restricted port, a controlling valve associated with said unit and for co-operating with said seat to normally close against the air pressure in said passage, the area of said valve being greater than that of the restricted port whereby an increased valve area is exposed to the line pressure when said valve is unseated, an armature associated with said valve, a magnet associated with said unit with the terminals of the pole pieces thereof extending laterally from opposite sides of said unit, said magnet attracting said armature to maintain said valve normally seated, and means for moving said armature within the field of said magnet on the interruption of the air pressure in said air line.

24. A railway signal system including a railway vehicle, a signal member, a pair of polarized magnets of different strength one associated with the railway vehicle and the other associated with the track and arranged with their poles reversed and one adapted to pass through the magnetic field of the other, whereby the magnetism of the stronger will neutralize the magnetism of the other and operate said signal member, and means co-operating with the poles of one

of said magnets for controlling the magnetic field of said magnet.

25. A railway signal system including a railway vehicle, a signal member, a pair of polarized magnets of different strength one associated with the railway vehicle and the other associated with the track and arranged with their poles reversed and one adapted to pass through the magnetic field of the other, whereby the magnetism of the stronger will neutralize the magnetism of the other and operate said signal member, and means associated with its poles for controlling the magnetic field of the stronger magnet.

26. A railway signal system including a railway vehicle, a pair of polarized magnets one associated with the railway vehicle and the other associated with the track and ar-

ranged with their poles reversed and one adapted to pass through the magnetic field of the other, a signal member normally held in inoperative position by one of said magnets, the movement of said magnets through their respective magnetic fields neutralizing the magnetism of one of said magnets to permit the operation of said signal, and electrically controlled means co-operating with the poles of one of said magnets for controlling the magnetic field of the magnet with which said means is associated.

In testimony whereof we have signed our names to this specification in the presence of the subscribing witness,

FOREE CHITTENDEN.
HOWARD S. FOLKER.
